UNITED STATES PATENT OFFICE.

WILLIAM G. HULLHORST, OF TOLEDO, OHIO, ASSIGNOR TO THE RANSOM & RANDOLPH COMPANY, OF SAME PLACE.

DESIGN FOR A DENTAL CABINET.

SPECIFICATION forming part of Design No. 23,189, dated April 10, 1894.

Application filed March 10, 1894. Serial No. 503,201. Term of patent 7 years.

To all whom it may concern:

Be it known that I, WILLIAM G. HULLHORST, of Toledo, county of Lucas, and State of Ohio, have invented a new and original Design for a Dental Cabinet; and I do hereby declare that the following is a full, clear, and exact description of the invention, which will enable others skilled in the art to which it appertains to make and use the same, reference being had to the accompanying drawing, and to the figures of reference marked thereon, which form part of this specification.

This invention relates to a new and original design for a dental cabinet.

The leading features of my design consist in a dental cabinet having a body, one side being higher than the other, there being a top extension of the back suitably ornamented, and a mirror in the extension opposite the higher portion of the top of the body, the body being provided with suitable receptacles arranged so as to give in conjunction with the top extension of the back and the legs, an ornamental appearance.

1 designates the body of the cabinet formed with legs 2. In the lower portion of the body is a receptacle closed by doors 3, and above

the same is a drawer 4, extending the full width of the cabinet; above the drawer on one side of the body is a rectangular receptacle 30 closed by a door 5, having a glass in the same, there being a slide 6 below the receptacle, and upon the opposite side of the cabinet is a series of drawers 7, extending to approximately one half the height of the said receptacle, the back 8, extending above the body and suitably ornamented as at 9, there being a mirror 10, to embellish the space opposite the upper extension of the half of the body, the legs being of a shape to give, in conjunction with the body and back extension as described, a pleasing and ornamental appearance to the cabinet.

What I claim is--

The design for a dental cabinet substantially as shown and described.

In testimony that I claim the foregoing as my own I hereby affix my signature in presence of two witnesses.

WILLIAM G. HULLHORST.
